(57) **CLAIM**

I claim the ornamental design for a motor scooter, as shown and described.

DESCRIPTION

FIG. 1 is a front view of a motor scooter showing my new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a diagonally right forward perspective view thereof;

FIG. 8 is a diagonally right backward perspective view thereof;

FIG. 9 is a diagonally left forward perspective view thereof; and,

FIG. 10 is a diagonally left backward perspective view thereof.
